DESIGN FOR TROUSERS

David Segelin and Solomon Segelin,
Rochester, N. Y.

Application September 21, 1934, Serial No. 53,357

Term of patent 7 years

To all whom it may concern:

Be it known that we, David Segelin and Solomon Segelin, citizens of the United States, residing at Rochester, in the county of Monroe and State of New York, have invented a new, original, and ornamental Design for Trousers, of which the following is a specification, reference being had to the accompanying drawing, forming a part thereof.

We claim:

The ornamental design for trousers as shown.

DAVID SEGELIN.
SOLOMON SEGELIN.
